UNITED STATES PATENT OFFICE.

ROBERT MIEHLE, OF CHICAGO, ILLINOIS, ASSIGNOR TO CONTINENTAL & COMMERCIAL TRUST & SAVINGS BANK, TRUSTEE, OF CHICAGO, ILLINOIS.

APPLICATION OF POWER TO RECIPROCATING-BED PRINTING-PRESSES.

1,143,425.

Specification of Letters Patent. Patented June 15, 1915.

Application filed September 5, 1911. Serial No. 647,584.

To all whom it may concern:

Be it known that I, ROBERT MIEHLE, a citizen of the United States, and a resident of Chicago, in the county of Cook and State 5 of Illinois, have invented certain new and useful Improvements in the Application of Power to Reciprocating-Bed Printing-Presses, of which the following is a specification.

10 This invention relates to improvements in reciprocating bed printing presses, and has for its object the controlling of the speed of the press by controlling the application of power thereto according to the requirements 15 conducive to obtaining the greatest speed.

In this class of printing presses a bed motion mechanism having a crank is used to slow down, stop, and start the type bed at the end of each stroke. Air cushions are 20 used in conjunction with the crank mechanism to assist in stopping the type bed at the end of each stroke. However there is a limit to the speed of the press on account of the shock produced by the stopping of the 25 type bed, when running over a certain limit of speed, which is very detrimental to the bed motion mechanism.

The object of this invention is to apply 30 the motive power so that the type bed will receive a variable speed, which will have the maximum speed at the middle of the stroke of the type bed and a minimum speed at the ends of the stroke. By reducing the speed at the ends of the stroke the momentum 35 of the type bed is diminished and it permits the press being run at a higher rate of speed before the limit of the speed of the press is reached, when the shock at the ends of the stroke is detrimental to the bed motion mechanism.

The invention also consists in the special forms of automatic mechanism herein set forth.

The nature of the invention will be more 45 fully understood from the subjoined description and the accompanying drawings which form a part of this specification.

In said drawing Figure 1 is an end view 50 of a reciprocating bed printing press equipped with the motor controlling mechanism. Fig. 2 is a partial left side view in elevation of the same. Fig. 3 is a left side view in elevation of the same, having the side frame removed in order to show the interior bed motion mechanism. Fig. 4 shows

a modified form of the invention. Fig. 5 shows another modification of the invention. Fig. 6 is a detail sectional view illustrating means for shifting the field magnet relatively to the rotatable armature to vary 60 the speed of the motor.

In said drawings, 1 is the electric motor from which the power is transmitted through the pulley, 2, and belt, 3, to the main drive pulley, 4, which is mounted on the main 65 drive shaft, 5, of the press.

6 is an automatic controller.

7 is the controlling lever of the controller, 6, for varying the speed of the motor. Pivotally attached to the lever, 7, is the connecting rod tube, 14, and the rod, 8, which is in turn pivotally connected to the impression cylinder shaft, 9, by the crank stud, 10. This stud is mounted eccentrically on said shaft. 75

21 is the regular motor controller, which is used by the operator to start the motor and press. To start the motor the lever, 22, is shifted to a position, which will give the press the proper speed desired. 80

By loosening the clamp screw, 13, the rod, 8, can be made shorter or longer by sliding the rod, 8, into or out of the hollow part, 14, and then tightening the clamp screw, 13. The rod, 8, can be allowed to slide freely in 85 the tube, 14, when it is desired not to use the automatic control, which occurs when the press is run at a slow speed for any length of time.

Referring to the mechanism for driving 90 the bed, I do not restrict my invention to any particular mechanism, as any mechanism may be substituted for driving the bed. In the drawings the bed 12 is provided on its under side with racks, C, C', 95

which are engaged alternately by a bed driving pinion, D, which gives to the bed its uniform to and fro motion and is journaled on the outer end of the oscillating arm I, which is raised and lowered at proper times by the cam i, on shaft N, which has on its outer end a gear F, which receives motion from pinion J on shaft 5. The gear D carries a wrist-pin or crank stud E, upon which is a roller E', which is adapted to engage with one of the end slots E² (see Fig. 4) formed between the end bars A', and the gates A² which are hinged to the press bed and swung on vertical axes. When the bed reaches the end of each stroke, and while 110

pinion D is out of mesh with both racks, the roller E' moves through the slot E² and reverses the bed by slowing down, stopping, and starting it in the reverse direction, during which period the pinion D is shifted from position to engage one rack into position to engage the other. The air cylinders G are fixed to the press frame and the air pistons H are fixed to the type bed. These air cushions assist in stopping the type bed and help to start it back on its return stroke. The gates A² are swung in and out of the path of the roller E' by the studs A⁴ working in the cam grooves A³.

15 As the gear D reaches the end of each rack, the roller E' is in position for engagement with one of the slots E², said roller E' bearing against the adjacent end bar A' and being at either its extreme up or 20 down position according to which reversal is about to be accomplished. Just before the gear D is disengaged from the rack the adjacent gate A², by the operation of the stud A⁴ in the cam groove A³, swings into 25 the path of said roller E', thus engaging said roller with the press bed. While thus engaged said roller E' slows down, stops, and reverses the press bed preparatory to the engagement of said gear D with the opposite rack. Just as the gear D is engaged with said opposite rack by the action of said cam i the gate A² is swung out of the path of the roller E', thus freeing it from 30 engagement with the press bed and gear D 35 then propels said press bed through the engaged rack to the other reversal of said bed, where the above mentioned operation is repeated in the opposite slot E². In the cycle of operation of the press the gear D 40 and roller E' receive three complete revolutions, one while gear D is engaged in each rack and one half a revolution while roller E' is engaged in each slot. The impression cylinder in this form of press, when operating, makes two complete revolutions for 45 each complete reciprocation of the type bed. As the impression cylinder revolves the stud 10 revolves with it, raising and lowering the rod 8, which transmits this motion to 50 the lever 7, thereby moving the finger 7' over the speed points b, so as to change the speed of the motor. The action of the stud 10 is so timed that the speed of the bed is gradually increased from the beginning of 55 the stroke until at the middle of the stroke it has reached its maximum speed. From this point the speed is gradually decreased until at the end of the stroke the minimum speed is reached. From this it will be readily understood that as the wrist-pin or 60 crank stud comes into action to stop the bed the momentum of the bed is not as it would be if the speed of the bed had not been decreased by decreasing the speed of the motor 65 as above referred to. Consequently by run-

ning the press at the points of reversal of the type bed at a speed, which is not detrimental to the bed motion mechanism, and increasing this speed during the stroke of the type bed a greater speed is obtained than by running the press uniformly at a speed, which is not detrimental to the bed motion mechanism at the points of reversal.

Fig. 4 shows the invention as applied to a shifting armature type motor. The crank, 15, is fixed to the impression cylinder shaft, 9. Pivots connected to the outer end of this crank is the rod, 16, at the outer end of which is fixed the rack, 17. Supporting this rack is the slide, 18, which is pivotally supported by the shaft, 19. Solidly fixed to the shaft, 19, is the gear, 20, which meshes with the rack, 17. As indicated in Figs. 4 and 6, the shaft 19 may be threaded and engage a threaded lug on the field magnet 200 of an electrical motor so that by turning shaft 19 the position of this field magnet relative to the armature 201 can be varied, thereby regulating or varying the speed of the motor. By revolving the shaft, 19, one way the armature is shifted and the speed of the motor is increased, and by revolving it in the opposite direction the speed of the motor is decreased. Thus, as the impression cylinder, 11, revolves, the crank, 15, revolves with it and through rod, 16, oscillates the rack, 17, which in turn oscillates the gear, 20, and shaft, 19, thereby varying the speed of the motor.

The control device shown in Fig. 4 is adapted to vary the speed of the motor by varying the strength of the magnetic influence that the field magnets of the motor exert upon the armature. The principle of operation being, that the influence that the magnetic field exerts upon the armature varies inversely as the length and directly as the area of the air gap between the armature and the field magnets. The armature and the inside surface of the field magnets are given a slight taper representing surfaces of truncated cones one within the other with the shaft of the motor as axis. Any lateral movement of the armature or field magnets will therefore vary the air gap and consequently vary the magnetic influence that the field magnets exert upon the armature, thus causing a variation in the speed of the motor. The shaft 19 controls the lateral position of the field magnets and armature with respect to one another, thus by revolving said shaft 19 the speed of the motor is varied.

A cam, 23, shown in Fig. 5, can be substituted for the crank, 15, or crank stud, 10, in which case the action of the rod, 16, or 8, can be varied, if desired, by forming the cam groove so as to give any desired motion to the controlling mechanism.

Having thus fully described my invention,

what I claim and desire to secure by Letters Patent is:

1. In a printing-press, the combination of a reciprocatory bed, means adapted to reciprocate said bed at a substantially uniform speed during the major portions of its strokes, such speed being substantially the same in both directions of movement of the bed and reversing its movements at the 10 ends of its strokes with gradual speed retardation and gradual speed acceleration in the opposite direction, and an electric motor to actuate said bed-driving means and operating at an increasing speed from sub-

stantially the beginning of a bed stroke and at a decreasing speed upon the cessation of the increasing speed to substantially the end of the bed stroke, substantially as described.

2. In a printing-press, the combination of a reciprocatory bed, means adapted to reciprocate said bed at a substantially uniform speed during the major portions of its strokes, such speed being substantially the same in both directions of movement of the bed and reversing its movements at the ends of its strokes with gradual speed retardation and gradual speed acceleration in the opposite direction, an electric motor to actuate said bed-driving means, and means operated 30 by the movement of a part of the printing-press to increase the speed of the motor from substantially the beginning of a bed stroke and decreasing its speed upon the cessation of the increasing speed to substantially the 35 end of the bed stroke, substantially as described.

3. In a printing-press, the combination of a revoluble impression cylinder, means to revolve said cylinder, a reciprocatory bed, 40 means adapted to reciprocate said bed at a

substantially uniform speed during the major portions of its strokes, such speed being substantially the same in both directions of movement of the bed and reversing its movements at the ends of its strokes with gradual speed retardation and gradual speed acceleration in the opposite direction, and an electric motor to actuate said cylinder - revolving means and said bed-driving means and operating at an increasing speed from substantially the beginning of a bed stroke and at a decreasing speed upon the cessation of the increasing speed to substantially the end of the bed stroke, substantially as described.

4. In a printing-press, the combination of a revoluble impression cylinder, means to revolve said cylinder, a reciprocatory bed, means adapted to reciprocate said bed at a substantially uniform speed during the major portions of its strokes, such speed being substantially the same in both directions of movement of the bed and reversing its movements at the ends of its strokes with gradual speed retardation and gradual speed acceleration in the opposite direction, an electric motor for actuating said cylinder-revolving and bed-driving means, and means operated by a movement of a part of the press-mechanism to gradually increase the speed of the motor from substantially the beginning of the bed-stroke and to gradually decrease the motor speed upon the cessation of the increasing speed to substantially the end of the bed stroke, substantially as described.
